UNITED STATES PATENT OFFICE.

ROBERT E. TABOR AND FRANCIS D. AMMEN, OF ST. LOUIS, MISSOURI.

MONOGRAM DEVICE.

Application filed July 3, 1922. Serial No. 572,509.

To all whom it may concern:

Be it known that we, ROBERT E. TABOR and FRANCIS D. AMMEN, citizens of the United States, residing in the city of St. Louis and 5 State of Missouri, have invented new and useful Improvements in a Monogram Device, of which the following is a specification.

It is a popular practice among owners of 10 automobiles to have their monograms painted upon the door of the automobile. This requires the services of an artist also necessitates the removal of such a monogram if it is found on a second-hand car when the 15 second-hand car is repurchased. The general object of the present invention is to provide simple and inexpensive means for producing a durable and artistic monogram of metal which will be of ornamental appearance, and which can be readily removed when desired.

Further objects of the invention will appear hereinafter.

The invention consists in the novel features, and in the general combination of parts to be particularly described herein-after, all of which contribute to produce a simple and efficient monogram device. A preferred embodiment of our invention will 25 be particularly described in the following 30 specification, while the broad scope of our invention will be pointed out in the appended claims.

In the drawing:—

35 Figure 1 is a front elevation showing a part of the upper portion of an automobile door with the monogram device attached thereto; one end of this plate is shown with a coating;

40 Figure 2 is a front elevation of the back-plate of the monogram device, removed from the door and without any monogram letters attached to it;

45 Figure 3 is a vertical section taken 3—3 of Figure 1;

Figure 4 is a front elevation of the letter R of the monogram and illustrating the same with means which we prefer to employ 50 for securing the letters to the back-plate;

Figure 5 is a similar view illustrating the letter E which forms a part of the monogram;

55 Figure 6 is a similar view showing the letter T of the monogram;

Figure 7 is a cross-section, taken on the

line 7—7 of Figure 6 to illustrate the preferred form of the elements of the letters, but showing the fastening device bent down at right-angles to the axis of the element or staff of the T on which this section is taken.

In practicing this invention, we provide a back-plate 1, the body 2 of which is preferably offset outwardly so as to give the plate a beveled or flanged edge 3 adapted to 60 seat against the vertical supporting face of the automobile door 4. By offsetting the body of the plate outwardly in this way, a slight recess is formed on the inner side of the plate so that when the plate is fastened 65 in position, a space or recess 5 is formed between the body of the plate and the face of the door.

In order to provide for securing the letters of the monogram in position, we prefer to provide a plurality of slots such as the slots 6 and we prefer to arrange these slots in rows extending substantially parallel with the upper and lower edges of the plate. The plate is of greatest width at 70 its middle point and is preferably of diamond shape substantially as illustrated. By providing these slots disposed in rows as described, it is possible for the same plate 75 to be used for securing any different letters 80 in position. It is simply necessary to provide three types of letters, one type corresponding to the letter R, another, corresponding to the letter T, shown at the middle of the plate in Figure 1, and another 85 type corresponding to the shape of the letter E of the monogram.

The letters are preferably formed of sheet metal, stamped out with a die so that the elements of the letters, such as the staff 7 of 90 the letter T, or any curved part, have a channel shape in cross-section such as illustrated in Figure 7, the channel or concave face 8 of the element being disposed on the inner side 95 of the letter. This gives the letter the appearance of a bevel edged letter.

The letters preferably carry the means for securing them in place, and this preferably consists of a flat spur, such as the spurs 9 indicated on the letter R in Figure 100 4. In forming the letter, these spurs are simply stamped out and obviously, can be produced in the same operation that produces the finished letter. In applying the letters to the plate, it is simply necessary 105 to bend each spur down at its root until it projects in a plane substantially at right

angles to the plane of the letter. The letter should then be applied to the plate so that its upper edge substantially coincides with the row of slots 6 near the upper edge of the plate and with its lower edge coinciding with the slots 6 near the lower edge of the plate. However, the edges of the letters should hide the slots under them. The spurs are then forced through the nearest 10 slots and are crimped on the inside or otherwise secured to prevent their removal.

The recess 5 affords space to receive these spurs as well as giving the plate the appearance of being a thick, solid plate.

15 We prefer to secure the back-plate 1 in position by means of screws 10 which are placed in openings 11 at the ends of the back-plate, and these openings are preferably disposed at the intersection of the rows 20 of slots.

25 While the slots 6 do not detract substantially from the ornamental appearance of the plate, if desired, we fill the slots with metallic composition, after which, if the outer face of the plate is nickel plated or otherwise covered with a coat 12 (shown at the right end of Figure 1), the slots between the letters will not be visible, and the face of the plate will look the same as that 30 of a solid plate.

35 In practice, the back-plate will be nickel or silver plated and the monogram letters gilded so as to insure that they will stand out and present a color contrasting well with the color of the back-plate.

40 It is understood that the embodiment of the invention described herein is only one of the many embodiments our invention may take, and we do not wish to be limited 45 in the practice of our invention nor in our claims, to the particular embodiment set forth.

What we claim is:—

1. In a monogram device to be fastened 45 on the face of a support, the combination of a diamond shaped back-plate having a row of slots extending along each edge thereof, a plurality of letters formed of sheet metal, the elements of the letters being of channel form with their concave side disposed toward the plate, said letters being

50 of at least three different types for position, respectively, at the center and ends of the plate, and so shaped that the lateral lines of projection of the letters of a monogram will be parallel with the edges of said plate, and so proportioned that when applied to the face of the plate, the upper edges of the letters will substantially coincide with the slots extending near the upper edges 55 of the plate, and the lower edges of the letters will substantially coincide with the lines of slots adjacent the lower edges of the plate, the material of said letters having integral spurs bent at right angles to the 60 plane of the body of the letters to lie flush with the edge thereof at the point of attachment and extending through some of the slots and securing the letters on the face of said plate, the channel form of the elements 65 of said letters operating to stiffen the same and enable projecting portions of the letters remote from the spurs, to maintain themselves rigidly in a fixed position and substantially against the face of the plate. 70

2. In a monogram device to be fastened on the face of a support, the combination of a diamond shaped back-plate having a row of slots extending along each edge thereof, a plurality of letters of at least three different types for position, respectively, at the center and ends of the plate, and so shaped that the lateral lines of projection of the letters of a monogram will be parallel with the edges of said plate, and so proportioned that when applied to the face of the plate, the upper edges of the letters will substantially coincide with the slots extending near the upper edges of the plate, and the lower edges of the letters will substantially coincide with the line of slots adjacent the lower edges of the plate, means carried by the letters for securing the same in said slots, said plate having openings 80 at the ends thereof substantially at the intersection of the rows of slots, to receive screws to secure the plate in position. 85

90 In testimony whereof, they have hereunto set their hands.

ROBERT E. TABOR.
FRANCIS D. AMMEN.
